UNITED STATES PATENT OFFICE.

ALBEN E. LUNDELL, OF NEW YORK, N. Y., ASSIGNOR TO WESTERN ELECTRIC COMPANY,
INCORPORATED, OF NEW YORK, N. Y., A CORPORATION OF NEW YORK.

TELEPHONE-EXCHANGE SYSTEM.

1,312,126.

Specification of Letters Patent.

Patented Aug. 5, 1919.

Application filed March 24, 1917. Serial No. 157,100.

To all whom it may concern:

Be it known that I, ALBEN E. LUNDELL, a citizen of the United States, residing at New York, in the county of Bronx and State of New York, have invented certain new and useful Improvements in Telephone-Exchange Systems, of which the following is a full, clear, concise, and exact description.

This invention relates to telephone exchange systems and particularly to improvements in listening-key arrangements for semi-automatic telephone exchanges.

In its preferred embodiment the invention is applied to a semi-automatic telephone exchange system in which an operator's keyboard may be connected by selectively operable means to any one of a plurality of senders arranged to control the setting of selector switches. Such systems as disclosed and claimed in my copending application, Serial No. 139,511, filed December 29, 1906, comprise a listening key sequence switch having contacts through which the above-mentioned connection between the keyboard and the sender may be established. In view of the fact that each operator's position is equipped with a plurality of listening-key switches and only a single keyboard, it is necessary to provide means whereby after the interconnection of the keyboard and a sender through the contacts of one listening key switch has been effected, the connection of this keyboard to another sender through contacts of another listening-key switch is prevented until the keys have performed their controlling function.

In order to permit the operator to receive a call while one of her listening-key sequence switches is in the listening-in position, the present invention contemplates the provision of means whereby a listening key sequence switch may be moved first into a listening-in position in which the keyboard is not connected to a sender, and then into a second listening-in position, in which the keyboard is connected to the sender provided that no other listening key switch is standing in the second listening-in position. As long as a listening key switch is standing in the second listening-in position, another switch is prevented from moving into that position.

It will be obvious to those skilled in the art that the use of the present invention is not limited to the particular type of switching and controlling devices disclosed, but is equally well applicable to manual telephone systems, and to systems in which other means than the one disclosed are used for connecting an operator's set to a connecting circuit.

Figures 1 to 8 of the drawings taken together illustrate diagrammatically as much of a semi-mechanical telephone exchange system as is necessary for an understanding of the present invention. The order in which the drawings should be considered is indicated in Fig. 9.

The reference numbers are used in such a manner that the hundreds digits of the numbers used in a figure correspond to the number of the figure. For the sake of convenience, the name used in the description for designating certain switching devices is displayed in the drawings adjacent to the showing of such devices. SN and MG designate sensitive and marginal relays, and H and L, high and low wound resistances, respectively.

Selector switches.

The selector switches used in this system are of the so-called power-driven panel type described in Patent No. 1,123,696 to E. B. Craft and J. N. Reynolds. For the purpose of distinguishing the various selector switches from each other, they will be hereinafter referred to in the following manner: District selector (Fig. 1), cord finder (Fig. 5), and sender selector (Fig. 5). Each of these selector switches has a vertically movable brush rod carrying brushes arranged to wipe over a commutator plate, and thus control the operation of the respective selector switches, and wipers arranged to engage contacts of a terminal bank, by means of which connections may be established. With the exception of the sender selector, which carries only one set of wipers, all the selectors referred to carry five sets of wipers, only one set of wipers being shown in the drawings. The terminal bank of the district selector and of the cord finder, comprises 500 rows of terminals divided into five sections, each

of the sections comprising one hundred rows of terminals. Each set of wipers is arranged to engage any row of terminals in a certain section, but rests normally 5 below the first row of terminals of its respective section. The wipers of a set are normally held apart by means of a cam, whereby they are out of the path of the terminals. By means of a tripping device associated with each of the selectors, any one of the wiper sets may be tripped to move its wipers into the path of the terminals of its respective section. The tripping device of the district selector and cord finder is of the 10 same type as described in Patent No. 1,177,044 to J. L. McQuarrie.

The brush rod of the sender selector carries a single set of wipers which are always in a tripped position and rest normally on 20 the lowermost row of terminals of a terminal bank. The wipers of the district selector are tripped only when they are moved out of normal, but before they reach the lowermost terminals of their respective terminal 25 sections.

Sequence switches.

The sequence switches shown in this system are of the type described in Patent No. 30 1,127,808. Sequence switch 108 controls, by means of its contacts, the circuits of the district selector. All the sequence switch contacts shown in Fig. 1 are controlled by the sequence switch 108. In Fig. 2, two sequence switches 202 and 210 are indicated. Sequence switch 202 is the listening key sequence switch and controls, with certain exceptions to be noted later, all the contacts shown below the horizontal dotted line in 35 Fig. 2, and sequence switch 210 is the key-control sequence switch controlling the contacts shown above the dotted line in this figure. Sequence switch 516 (Fig. 5) controls the circuits of the cord finder and the 40 sender selector. All the sequence switch contacts shown in this figure, with the exception of those within the dotted rectangle, are controlled by this sequence switch. The latter mentioned contacts are controlled by 45 an allotter 583 of the sequence switch type. Sequence switches 613 and 600 (Fig. 6) control, by means of their contacts shown to the left and right of the vertical dotted line of this figure, the circuits of a sender, and 50 the circuits of a plurality of registers, respectively. The sequence switch contacts shown in Fig. 7 are controlled by sequence switch 706. This sequence switch will be referred to as a class register controller.

60

Keyboard.

The operator's keyboard is shown in Figs. 3 and 4. When, in any of the rows, a key is depressed, it is locked by mechanical means, 65 which may be released in response to the

energization of a magnet 342, one being provided for each row of keys. There are nine rows of keys referred to as the office, tandem hundreds, tandem tens, tandem units, thousands, hundreds, tens, units and stations 70 keys. Each row, with the exception of the office and stations keys, comprises keys numbered 0 to 9, each key controlling as many contacts as is necessary for controlling the selectors and registers. The number of 75 office keys depends on the traffic requirements. The office keys are the equivalents of the tandem hundreds, tandem tens and tandem units keys; that is to say, the depression of one office key results in the same 80 combination of impulses as the depression of a certain combination of tandem hundreds, tens and units keys. One office key is provided for controlling the seizure of a trunk leading to an important office, where- 85 as other offices may be reached by depressing a prescribed combination of tandem keys.

Registers.

Figs. 7 and 8 represent ten registers. 90 These registers will be referred to as: 1, district group or tandem tens; 2, office brush; 3, office group or tandem units; 4, class; 5, incoming brush; 6, incoming group; 7, final brush; 8, final tens; 9, final 95 units; and 10, stations registers. With the exception of the class and incoming group registers, each register comprises three relays, two of the relays being of a marginal character and one of the relays sensitive. 100 The incoming group register comprises one sensitive and one marginal relay, and the class register, two sensitive and three marginal relays. Each of the register relays is provided with a locking winding, and depending on the combination in which the relays of a certain register are actuated, the 105 operation of the sender is determined.

Sender.

The sender (Fig. 6) comprises a pair of wipers 635 and 636 arranged to be moved step by step over a circle of terminals in the direction indicated by the arrow, in response to each complete operation (energization 115 and deenergization) of a magnet 634. The terminals are divided into four sections A, B, C and D. The terminals of sections A and B are connected to conductors 657 and 642, respectively. The five terminals of sections 120 C and D are numbered 0 to 4, and the terminals of these two sections designated by the same numerals are connected in multiple. The two terminals numbered 0 are interconnected by means of sequence switch 125 springs 664 and 665 in certain positions of sequence switches 600 and 613. Magnet 634 may be energized and deenergized under the control of a stepping relay 632. A relay 633 controls the stopping of the sender wipers 130

in a certain position determined by the setting of the various registers. The numerals appearing in the circles at the contacts of the various register relays indicate the terminal of the sender to which those contacts are connected.

Detailed description.

A subscriber at substation 100 (Fig. 1), desiring to obtain a connection removes his receiver from the switchhook, whereupon a line relay LR becomes energized and causes the lighting of a calling lamp CL. An operator, whose head set is indicated at 200, inserts thereupon a plug 101 into an answering jack 102 in which the calling subscriber's line terminates. A circuit is closed thereupon from grounded battery, through the winding of a cut-off relay CO, the sleeve contacts of jack 102 and plug 101 and the winding of relay 103 to ground, and another circuit from the plus pole of battery, through the primary winding of a repeating coil 104, the winding of an answering supervisory relay SR, the lower limb of cord circuit 105, the ring contacts of plug 101 and jack 102, the calling substation 100, the tip contacts of jack 102 and plug 101, the upper limb of cord circuit 105 and the 25 primary winding of repeating coil 104 to the minus pole of battery. Relays CO, 103 and SR become energized. The relay CO disconnects relay LR, whereupon lamp CL becomes extinguished.

30 Relay 103 closes a circuit from ground through its armature and front contact, conductor 106, the lower right-hand contact of sequence switch spring 201, and the power magnet of sequence switch 202 to grounded battery. Under the control of its normal contact 203, the sequence switch 200 is moved 35 out of position 1 and into position 7.

Each operator's position is equipped with one telephone set 200, a relay 280, and a 40 relay 281. For each cord like 105, one listening key sequence switch like 202 is provided, and by means of any of these listening key sequence switches, the telephone set 200 may be connected to a calling line through a cord 45 circuit. The circuits of all the listening key sequence switches are like those of switch 202.

As soon as the sequence switch 202 reaches position 7, a circuit is closed from 50 ground through the lower contact of sequence switch spring 283 and the winding of the relay 281 to grounded battery. The relay 281 becomes energized and prevents the connection of the operator's telephone set 55 200 by means of another listening key sequence switch to another calling line in position 8 of said other listening key sequence switch. The operator's telephone set 200 is connected through sequence switch 60 contacts 204 and 205 to the cord circuit 105

and thus the operator is enabled to converse with the calling subscriber. A circuit is also closed from ground through the armature and front contact of relay 103, conductor 106, sequence switch contact 206, a 70 conductor 207, the upper right-hand contact of sequence switch spring 107, and the power magnet of sequence switch 108 to grounded battery. The sequence switch 108 is moved out of position 1 and under the 75 control of its normal contact 109 into position 2.

If the operator is not listening in through another cord then all the listening key sequence switches, except 202, are in the 80 normal position 1 or in the listening-out position 12. In these positions of the other sequence switches, the contacts of sequence switch springs corresponding to 283, such as 283' are open and thus the relays 280 and 85 281 cannot be energized under the control of the other listening key sequence switches. Relay 280 being deenergized, a circuit is closed from ground through the armature and back contact of this relay, the upper 90 contact of sequence switch spring 282, and the power magnet of sequence switch 202 to grounded battery, for driving this sequence switch out of position 7 and into position 8. As soon as the sequence switch 95 202 reached position 7, a circuit was closed from ground, through sequence switch contact 208, contact 209 of sequence 210, and the winding of a relay 211 to grounded 100 battery. The relay 211 becomes energized and closes a locking circuit for itself through its right-hand front contact and armature and sequence switch contact 208. The relay 281 being now deenergized, 105 the operator's telephone set is connected to the cord circuit 105 through the armatures and contacts of relay 281 and the upper contacts of sequence switch springs 204 and 205. In position 8 of the sequence switch 202, the upper contact of sequence switch 110 spring 283 is closed, whereupon the relay 280 becomes energized and prevents the movement of another listening key sequence switch out of position 7.

From the above description it will be 115 obvious that if another listening key sequence switch, such as the one controlling the contact 283', is in position 7, then the relay 281 is energized and prevents the connection of the set 200 to the cord circuit 105 120 in position 8 of the sequence switch 202.

If the sequence switch controlling contact 283' is in position 8, the relay 280 is energized and prevents the movement of sequence switch 202 into position 8. 125

As indicated in Fig. 2 of the drawings, the relay 211 is common to a plurality of listening key switches and thus it may be energized also in response to the closure of a sequence switch contact 208' controlled 130

by another listening-key sequence switch of the operator.

Setting of the cord finder and the sender selector.

Assuming that several cord circuits are simultaneously taken into use by various operators, and thus several sequence switches like 108 are in position 2, a circuit is closed 10 from ground, through the lower right-hand contact of sequence switch spring 112, conductor 111 (Figs. 1, 2 and 5), the lower armature and back contact of a relay 500, the lower armature and back contact of a 15 relay 501, a resistance 502 and the winding of a marginal relay 503 to grounded battery. A similar circuit is closed for the relay 503 by each of the sequence switches corresponding to 108. Each of these 20 circuits includes a resistance like 502 and, for this reason, the relay 503, which is marginal in operation, is operated. Relays 500 and 501, resistance 502 and the conductors shown in the lower left-hand corner of 25 Fig. 5, are individual to the link circuits 105 of the operator's position. Similar apparatus are individual to each of the other positions. Relay 503 closes a circuit from ground, through its armature and 30 front contact, the armature and back contact of a relay 504, and the back contact and armature of a magnet 505 to grounded battery. Magnet 505 interrupts its own 35 circuit and thus causes, by means of a pawl 506 fixed to its armature, the stepping of wipers 507 and 508 mounted on a ratchet wheel 509. The wipers 507 and 508 are arranged to traverse terminals representing 40 groups of link circuits. As soon as the wiper 508 engages terminal 510 individual to the group in which the link circuit 105 belongs, a circuit is closed from grounded battery, through the winding of relay 504, wiper 508, terminal 510, the lower back 45 contact and armature of relay 501, the lower back contact and armature of relay 500, conductor 111 and sequence switch contact 110 to ground. Relay 504 becomes energized and opens in its back contact, the operating 50 circuit of magnet 505, whereupon the wipers are arrested. Relay 504 closes also a circuit from ground, through the armature and front contact of relay 503, its armature and front contact, the armature and back 55 contact of a relay 511, and the left-hand winding of a relay 512 to grounded battery. Relay 512 closes a locking circuit for itself from ground, through its armature, front contact and right-hand winding, wiper 507, 60 a terminal 513 individual to the group of cords 105, the lower winding of relay 501, and the windings of relays 511 and 514 to grounded battery. Relays 511, 514 and 501 become energized. When relay 501 65 opens in its lower back contact the energiz-

ing circuit of relay 503, this relay is maintained energized by a circuit closed through the lower back contact of another relay 501 individual to another group of calling link circuits. Relay 504 becomes deenergized. 70 Relay 514 closes a circuit from ground through its armature and front contact, the upper left-hand contact of sequence switch spring 515, and the left-hand winding of a relay 517 to grounded battery. As will be 75 hereinafter set forth, only one sequence switch like 516 is in position 1 at a time, and for this reason the energization of relay 514 results in the energization of only one relay like 517. 80

Upon the energization of relay 501 a circuit is closed from ground, through the lower right-hand contact of sequence switch spring 112, conductor 111, the lower armature and back contact and the lower armature and front contact of relays 500 and 501 respectively, and the winding of a trip magnet 541 to grounded battery. The trip magnet 541, by attracting its armature, moves a trip finger 542 into the path of a catch 90 543 carried by cam 535. The connection of ground to the lower front contact of relay 501 results also in the shunting out of relay 512 which thereupon becomes deenergized. Before the wipers of set 533 engage the 95 lowermost terminals of bank 534 as will be hereinafter set forth, the trip finger actuates catch 543, causing thus cam 535 to be removed from between the wipers; whereupon these wipers are permitted to move in alignment with the terminals of the bank. 100

Upon the deenergization of relay 504, relay 503 causes magnet 505 to move the wipers 507 and 508 away from terminals 513 and 510. Relay 504 breaks the circuit of magnet 505 in the same manner as above described when wiper 508 finds the terminal individual to the group containing the next calling link circuit. 105

The wipers of the sender selector 518 110 are normally resting on a set of contacts in which conductors leading to a sender terminate. Supposing that this sender is busy, as will be hereinafter set forth, ground is connected to terminal 519. For this reason a locking circuit is closed for relay 517, through wiper 520 of the sender selector 518, and the right-hand armature, front contact and winding of the relay 517. Upon the energization of relay 517, a circuit is 115 closed from ground, through the left-hand armature and front contact of this relay, the upper right-hand contact of sequence switch spring 521 and the winding of a relay 522 to grounded battery. Relay 522 closes 120 a circuit from ground, through its right-hand armature and front contact, the lower left-hand contact of sequence switch spring 523 and the power magnet of sequence switch 516 to grounded battery. The se- 125 130

quence switch 516 is thereupon moved out of position 1, and under the control of its normal spring 524, into position 2. A circuit is now closed from grounded battery, 5 through the winding of a magnet 525, the upper contacts of sequence switch spring 526 and the right-hand front contact and armature of relay 522 to ground, and another circuit from ground, through the left- 10 hand armature and front contact of relay 517, the upper left-hand and lower right-hand contacts of sequence switch spring 527, and the winding of a magnet 529 to grounded battery. Magnets 525 and 529 become energized. 15 By attracting its armature magnet 525 pressed brush rod 530 of cord finder 531 against a roller 532 constantly rotating in the direction indicated by the arrow. The brush rod 530 carries a plurality of sets of wipers similar to 533. These wipers are arranged to engage the sections of the terminal bank 534 comprising sets of terminals representing cord circuits such as 105, but the wipers of each set are normally held apart by means of a cam like 20 535. A brush 536, arranged to engage various segments of a commutator plate, is also carried by brush rod 530. As soon as the brush rod has been moved in an upward direction far enough to permit brush 536 to 25 engage conducting segment 537, which happens prior to the engagement by the wipers 533 of the lowest row of terminals of the respective bank section, a circuit is closed from ground, through brush 536, conducting plate 537, the right-hand contacts of sequence switch spring 560, the upper front contact and armature of relay 501, and the winding of relay 500 to grounded battery. 30 The relay 500 becomes energized and closes a locking circuit for itself through conductor 111 and sequence switch spring 112, to ground, whereupon relays 501, 511 and 514 become deenergized. Relay 514 closes a 35 circuit from ground, through its armature and back contact, the upper right-hand contact of sequence switch spring 523, and the power magnet of sequence switch 516, to grounded battery, whereupon the sequence switch is moved out of position 2 and into position 3. Relay 511 being deenergized, the relay 512 is permitted to operate under the control of the next calling cord circuit. 40 When the sequence switch 516 moved out of position 2, relay 522 was maintained energized by a circuit extending from ground, through its winding, the upper left-hand contact of sequence switch spring 521, 45 and the right-hand back contact and armature of a test relay 545 to ground. As soon as the wipers 533 engage the set of terminals representing cord 105, a circuit is closed from ground, through the upper right-hand contact of sequence switch spring 112, a con-

ductor 186, a resistance 212, conductor 213, terminal 546, wiper 547, the lower right-hand contact of sequence switch spring 547, and the windings of relay 545 to grounded battery. If full battery potential exists on 70 terminal 546; that is to say, if no other cord finder engages with its test wiper this terminal, then relay 545, which is marginal in operation, becomes energized and closes a locking circuit for itself through its left- 75 hand armature and front contact, and conductor 213. By short-circuiting its high resistance left-hand winding, this relay decreases the potential on terminal 546, so as to prevent the energization of a test relay 80 associated with another cord finder, when such cord finder tests the terminals representing cord 105. As a precautionary measure, other means are provided in the right-hand armature and front contact of 85 relay 545, and a resistance 548, for decreasing the potential on test terminal 546 in position 2 to 2½ of sequence switch 516. By opening its right-hand back contact, relay 545 opens the circuit of relay 522. 90 This relay, however, remains energized, ground being connected to its winding through brush 536 as long as this brush rests on a conducting plate 549. As soon, however, as the brush 536 engages one of 95 the insulated segments 550, which indicates that the wipers 533 are centered on the selected set of terminals, the relay 522 becomes deenergized and closes a circuit from ground, through its right-hand armature 100 and back contact, the upper left-hand contact of sequence switch spring 523, and the power magnet of sequence switch 516 to grounded battery, for driving this sequence switch out of position 3 into position 4. As 105 soon as relay 522 becomes deenergized, the circuit of magnet 525 is opened, and thus the brush rod 530 is arrested with the wipers 533 in engagement with the selected set of terminals. 110

In position 4 of sequence switch 516, a circuit is closed from ground, through the contact of sequence switch spring 580, the upper left-hand contact of spring 581 and the power magnet of allotter 583, to grounded battery. The allotter is moved out of 115 position 1 and under the control of its normal contact 584 into position 2. The allotter closes now the contact of its spring 582 and causes the preselection of a cord finder and 120 a sender selector switch by moving their associated sequence switch out of position 18 into position 1, as will be hereinafter set forth in connection with sequence switch 516.

The magnet 529, by attracting its armature, presses brush rod 552 against a roller 553, constantly rotating in the direction indicated by the arrow. The brush rod 552 of sender selector 518 carries a set of wipers 554 and a brush 555. The energizing circuit of 125 130

magnet 529 will be maintained closed while relay 517 is energized, and the upper left-hand and lower right-hand contacts of sequence switch spring 527 are closed. For this reason the wipers 554 continue to move in an upward direction until wiper 520 engages a terminal 551 individual to a sender, the sequence switch 600 of which is in position 1, and maintains the upper contacts of its spring 601 open, and which sender is not occupied by another sender selector. The relay 517, although its above traced locking circuit is open, is then maintained energized by a circuit extending from ground, through its left-hand armature and front contact, the upper left-hand contact of sequence switch spring 527, brush 555, conducting plate 556, the upper right-hand contact of sequence switch spring 515, and the left-hand winding of relay 517 to grounded battery, as long as brush 555 engages the conducting segment 556. When, however, the brush 555 engages an insulated segment 558, indicating thus that the wipers 554 are centered on the selected set of terminals, relay 517 becomes deenergized, opens the circuit of magnet 529 and closes a circuit from ground, through its left-hand armature and back contact, the lower right-hand contact of sequence switch spring 523, and the power magnet of sequence switch 516 to grounded battery, for moving this sequence switch out of position 4 and into position 15.

It may be seen from the above that if a plurality of sequence switches like 108 are moved into position 2 at the same time, then, under the control of the devices and circuits represented in the lower part of Fig. 5, one call is taken care of and the setting of another pair of cord finder and sender selector switches is delayed until the wipers 533 of cord finder 531 are tripped, *i. e.*, until the five sets of wipers carried by brush rod 530, have been moved a sufficient distance so as to prevent the tripping of another set of brushes of this cord finder in response to the energization of another trip magnet, such as 541^a.

If only a single sequence switch like 108 is moved into position 2, it is not necessary to operate the above described barring means. Due to the marginal character of relay 503, it will not operate in response to current flowing through a circuit which contains only one resistance like 502. A circuit will therefore be closed from ground, through the back contact of relay 503, the left-hand armature and back contact of relay 511, the upper winding of the relay 501 individual to a group of cord circuits 105, the upper back contact and armature of relay 500, conductor 585, and the contact of sequence switch spring 110 to grounded battery. Relay 501 becomes energized and closes a circuit from grounded battery,

through the windings of relays 514 and 511, the lower winding, front contact and armature of relay 501, the lower back contact and armature of relay 500, conductor 111, and the lower right-hand contact of sequence switch spring 112, to ground. A branch of this circuit extends from grounded battery, through the winding of trip magnet 541 to the lower front contact and armature of relay 501. The relays 514 and 511 and the magnet 541 become energized and the switches 518 and 531 are operated in the same manner as above described.

Upon the setting of cord finder 531 and sender selector 518, the sequence switches are in the following positions: sequence switch 108 in position 2, sequence switch 202 in position 8, sequence switch 516 in position 15, and all the other sequence switches in position 1.

85

Adjustment of the keyboard.

Supposing that the called subscriber's number is B-9876, the operator depresses the B office key, the number 9, 8, 7, 6 thousands, 90 hundreds, tens and units keys and a start key 404, respectively, whereupon the keys remain locked in their depressed position.

In response to the depression of office key B, contacts 353, 354, 355 and 356 of this key 95 are closed. The closure of these contacts results in the establishment of the following circuits:

1. From grounded battery, through the winding of a relay 349, contact 353, conductor 357 (Figs. 3, 2 and 1), the winding of a relay 113_a, to ground. Relays 113_a and 349 become energized.
2. From ground, through the winding of a relay 214, a conductor 215, the winding of relay 303, contact 354, and the winding of a relay 305, to grounded battery. Relays 214, 303 and 305 become energized.
3. From grounded battery, through a resistance 358, conductor 359, key contact 355, conductor 360, the winding of relay 311, conductor 312, conductor 215, and the winding of relay 214 to ground. Relay 311 becomes energized.
4. From grounded battery, through the winding of a relay 344, conductor 361, key contact 356, conductor 346, the right-hand winding of a relay 329, the winding of a relay 313, conductors 312 and 215, and the winding of relay 214 to ground. Relays 344, 329 and 313 become energized.

In response to the energization of relay 344, a circuit is closed from grounded battery through the power magnet of sequence switch 210, the upper left-hand contact of sequence switch spring 237, a conductor 264, the left-hand front contact and armature of relay 344, a conductor 263, the left-hand inner front contact and armature of relay 211, a sequence switch contact 262, a conductor 130

132, and the upper left-hand contact of sequence switch spring 112 to ground. The sequence switch 210 is moved out of position 1, and under the control of its normal 5 contact 265 into position 2. As above stated only one listening key sequence switch can be in position 8 at a time and thus only one of these sequence switches can connect the keyboard to a set of registers through its 10 contacts 224, 226 and 228.

Setting of the class register.

As soon as sequence switch 210 reaches position 1 $\frac{1}{4}$, a circuit is closed from grounded 15 battery, through the relatively low resistance 319, the front contact and armature of relay 303, conductor 231, the lower right-hand contacts of sequence switch springs 230 and 229, the upper contact of sequence 20 switch spring 228, conductor 566, terminal 579, wiper 528, sequence switch contact 565, wiper 540, terminal 539, conductor 620, the upper right-hand contact of sequence switch 25 spring 619, conductor 710, and the left-hand windings of a marginal relay 704 and a sensitive 30 relay 709, to ground. Due to the relatively low resistance of the circuit, both relays become energized.

In position 1 $\frac{1}{4}$ of sequence switch 210, another circuit is closed from grounded battery, through the relatively low resistance 339, the front contact and armature of relay 349, a conductor 363, the upper contacts of sequence switch springs 266 and 226, conductor 227, terminal 578, wiper 576, sequence switch contact 563, wiper 538, terminal 557, conductor 564, the right-hand contact of sequence switch spring 615, a conductor 616, and the left-hand windings 40 of a marginal relay 702 and a sensitive relay 703 to ground. Due to the relative low resistance of the circuit both relays 702 and 703 become energized.

When the sequence switch 210 reaches position 2, a circuit is closed from ground, through the upper armature and back contact of a relay 219, the low resistance left-hand winding of a relay 220, a conductor 221, the front contact and armature of relay 305, conductor 318, the lower right-hand contacts of sequence switch springs 222 and 223, the upper left-hand contact of sequence switch spring 224, conductor 225, terminal 577, wiper 575, the left-hand contacts of sequence switch spring 560, wiper 544, terminal 559, conductor 561, the upper contacts of sequence spring 603, conductor 604, the left-hand winding of a marginal relay 700, conductor 701, the upper right-hand contact of sequence switch spring 605, and the winding of a relay 606, to grounded battery. Relays 220, 606, and, due to the relatively low resistance of the left-hand winding of relay 220, the marginal relay 700, become energized.

Relay 606 closes a circuit from ground, through its armature and front contact, the lower contacts of sequence switch spring 601, and the winding of a relay 608 to grounded battery. Relay 608 closes a circuit from 70 ground, through its lower armature and front contact, the upper left-hand contact of sequence switch spring 609 and the power magnet of sequence switch 600 to grounded battery, for moving this sequence switch 75 out of position 1; under the control of its master contact 668, the sequence switch 600 is moved into position 2. The relay 608 does not become deenergized upon the opening of the lower contacts of sequence switch 80 spring 601, a locking circuit being closed from grounded battery, through the winding, and upper front contact and armature of this relay, conductor 610, terminal 551, wiper 520, the right-hand armature and back 85 contact of test relay 517, and the left-hand contact of sequence switch spring 562, to ground. A circuit is now closed from ground, through sequence switch contact 611, the left-hand contact of sequence switch 90 spring 612 and the power magnet of sequence switch 613 to grounded battery. Sequence switch 613 is moved out of position 1 and under the control of its normal contact 614 into position 2.

As soon as sequence switch 600 reaches position 2, a circuit is closed from grounded battery, through the upper contact of sequence switch spring 621, conductor 712, and then through the right-hand windings, 100 armatures and front contacts of relays 700, 704, 709, 702 and 703 in multiple, to ground. These relays remain thus locked up. Due to the fact that all the class-register relays are energized, the circuit which was prepared from ground through sequence switch contact 617, conductor 618 and any one of the sequence switch springs 739, 711, 708 and 740 for the class-register sequence switch 706 and relay 705, will be maintained 105 open in the outer back contacts of the class register relays. The sequence switch 706 remains thus in position 1 and the relay 705 does not become energized.

Normally a shunt is placed around the 115 winding of relay 219, through the lower armature and back contact of this relay and the left-hand back contact of relay 220. As soon as relay 220 becomes energized and opens its left-hand back contact the relay 219 is permitted to become energized by current flowing from ground, through its winding, the left-hand contact of a sequence switch spring 218, and a resistance 217 to grounded battery. The ground that was 120 supplied through the upper back contact of relay 219 is now supplied through the left-hand front contact of relay 220 for maintaining the latter energized.

As soon as sequence switch 600 reaches 130

position 2, a circuit is closed from grounded battery, through the power magnet of sequence switch 600, the armature and back contact of a relay 623, the left-hand contact 5 of sequence switch spring 622, and the front contact and armature of relay 606 to ground. The sequence switch 600 moves out of position 2 into position 3. Due to the opening of the upper right-hand contact of sequence 10 switch spring 605, relays 606 and 220 become deenergized and the latter closes a circuit from ground through its left-hand armature and back contact, the lower armature and front contact of relay 219, the sequence 15 switch spring 232, the left-hand back contact and armature of relay 233, and the power magnet of sequence switch 210 to grounded battery. The sequence switch moves out of position 2 into position 3, 20 whereby relay 219 becomes deenergized.

Setting of the district group register.

When the sequence switches 210 and 600 reach position 2 $\frac{1}{4}$, a circuit is prepared 25 from ground through the left-hand windings of a marginal relay 718, and a sensitive relay 717, conductor 625, the upper left-hand contact of sequence switch spring 624, conductor 561, terminal 559, wiper 544, the 30 left-hand contacts of sequence switch spring 560, wiper 575, terminal 577, conductor 225, the upper left-hand contact of sequence switch spring 224, the right-hand contact of sequence switch spring 223, the upper right-hand contact of sequence switch spring 222, and conductor 267. Due to the fact that 35 neither of the relays 310 and 351 is energized, this circuit is not completed and therefore relays 718 and 717 remain deenergized. 40

When the sequence switches 210 and 600 reach position 3 a circuit is closed from grounded battery through the windings of a relay 623, the lower contact of sequence 45 switch spring 627, conductor 720, the left-hand winding of a marginal relay 719, conductor 626, conductor 620, terminal 539, wiper 540, the sequence switch contact 565, wiper 528, terminal 579, conductor 566, the 50 upper left-hand contact of sequence switch spring 228, the lower right-hand contact of sequence switch spring 229, the upper right-hand contact of sequence switch spring 230, conductor 321, the armature and front contact of the relay 311, conductor 320, conductor 331, the windings of relay 233, and the upper back contact and armature of relay 234 to ground. Relays 233 and 623 become energized. Due to the fact, however, 55 that the left-hand winding of relay 233 is of a relatively high resistance, the relay 719 remains deenergized. Upon the energization of relay 233, a shunt is removed from around the winding of relay 234 in the same

manner as was described in connection with 65 relay 219, and this relay becomes energized by current flowing in the circuit extending from grounded battery through resistance 217, the right-hand contact of sequence switch spring 218, and the winding of relay 70 234 to ground.

Relay 623 closes a circuit from ground through the armature and back contact of relay 606, the right-hand contacts of sequence switch spring 622, the front contact 75 and armature of relay 623, and the power magnet of sequence switch 600 to grounded battery, for moving this sequence switch out of position 3 and into position 4. Upon the opening of the lower contact of sequence 80 switch spring 627, the circuit of relays 623 and 233 is broken and the latter closes a circuit from ground through its armature and back contact, the lower armature and front contact of relay 234, the right-hand back 85 contact and armature of relay 220, the upper left-hand contact of sequence switch spring 237, and the former magnet of sequence switch 210 to grounded battery, for moving sequence switch 210 out of position 90 3 and into position 4.

District translation.

When the sequence switches 210 and 600 move through position 3 $\frac{1}{4}$, a circuit is prepared 95 from ground through the left-hand winding of relay 742, conductor 741, the lower right-hand contact of sequence switch spring 619, conductor 620, terminal 539, wiper 540, the sequence switch spring 565, 100 wiper 528, terminal 579, conductor 566, the upper contact of sequence switch spring 228, the right-hand contact of sequence switch spring 229, the upper left-hand contact of sequence switch spring 230, conductor 325, 105 and then, due to the fact that relay 306 has not been energized, this circuit will not be completed, and thus the relay 742 arranged to control the translation remains deenergized. 110

Office translation.

When the sequence switches 210 and 600 reach position 4, a circuit is closed from 115 ground through the upper armature and back contact of relay 219, the left-hand winding of relay 220, conductor 221, conductor 323, the back contact and armature of relay 322, conductor 238, the upper left-hand contact of sequence switch spring 222, 120 the right-hand contact of sequence switch spring 223, the upper contact of sequence switch spring 224, conductor 225, terminal 577, wiper 575, the left-hand contacts of sequence switch spring 560, wiper 544, terminal 559, conductor 561, the upper contact of sequence switch spring 603, conductor 604, the left-hand winding of marginal relay 125

721, conductor 628, the upper left-hand contact of sequence switch spring 605, and the winding of relay 606 to grounded battery. Relays 606 and 220, due to the relatively low 5 resistance of the circuit relay 721, become energized. The relay 721 closes a locking circuit for itself through its right-hand armature, front contact and right-hand winding in multiple with the class register 10 relays. Relay 220 opens the shunt around relay 219 and this relay becomes energized in the above described manner. Relay 606 closes a circuit for moving the sequence switch 600 out of position 4 and into position 15 5, whereupon the upper left-hand contact of sequence switch spring 605 will be opened and relay 220 by releasing its armatures recloses the above-traced circuits and causes the movement of sequence switch 210 20 out of position 4 and into position 5.

Setting of the office brush register.

When the sequence switches 210 and 600 pass through position 3 $\frac{1}{4}$ a circuit is prepared from ground through the left-hand windings of a marginal relay 724 and a sensitive relay 725, conductor 726, the upper right-hand contact of sequence switch spring 624, conductor 561, terminal 559, wiper 544, 25 left-hand contacts of sequence switch spring 560, wiper 575, terminal 577, conductor 225, the upper left-hand contact of sequence switch spring 224, the right-hand contact of sequence switch spring 223, the lower left-hand contact of sequence switch spring 222, conductor 239, and then, due to the fact that neither of the relays 347 and 317 is energized, this circuit is not completed and relays 724 and 725 remain deenergized. 30

When the sequence switches reach position 5, a circuit is closed from ground through the upper armature and back contact of relay 234, the windings of relay 233, conductor 331, conductor 320, the back contact and armature of relay 328, conductor 240, the lower left-hand contact of sequence switch spring 230, the right-hand contact of sequence switch spring 229, the upper contact of sequence switch spring 228, conductor 566, terminal 579, wiper 528, sequence switch contact 565, wiper 540, terminal 539, conductor 620, conductor 626, the left-hand winding of a marginal relay 722, conductor 723, the upper contact of sequence switch spring 627, and the winding of relay 623 to grounded battery. Relays 623 and 233 become energized. Due to the fact, however, that the windings of relay 233 are of a relatively high resistance, the marginal relay 722 will not become energized. The relay 623 closes a circuit in the above described manner for driving the sequence switch 600 out of position 5 and into position 6. The relay 233 permits the energization of relay

234 and, upon the opening of the circuit by 65 sequence switch 600, relay 233 causes the movement of sequence switch 210 out of position 5 and into position 6.

Setting of the office group register.

When the sequence switch 600 and sequence switch 210 move into position 5 $\frac{1}{4}$ a circuit is closed from grounded battery through resistance 319, conductor 324, the front contact and armature of relay 329, 75 conductor 242, the upper left-hand contact of sequence switch spring 241, the right-hand contact of sequence switch spring 229, the upper contact of sequence switch spring 228, conductor 566, terminal 579, wiper 528, 80 sequence switch contact 565, wiper 540, terminal 539, conductor 620, the upper left-hand contact of sequence switch spring 619, conductor 715, the left-hand windings of a sensitive relay 714, and a marginal relay 85 713 to ground. Due to the fact that the resistance 319 is relatively low, both relays 714 and 713 become energized and lock up through their right-hand armatures, front contacts, and windings, and conductor 716 90 in multiple with the other register relays.

When the sequence switches reach position 6 a circuit is closed from ground through the upper armature and back contact of relay 219, the low resistance left-hand winding of relay 220, conductor 221, conductor 323, the front contact and armature of relay 313, conductor 244, the lower left-hand contact of sequence switch spring 243, the right-hand contact of sequence switch spring 223, 100 the upper contact of sequence switch spring 224, conductor 225, terminal 577, wiper 575, the left-hand contact of sequence switch spring 560, wiper 544, terminal 559, conductor 561, the upper contact of sequence switch spring 603, conductor 604, the left-hand winding of a marginal relay 727, conductor 629, the lower left-hand contact of sequence switch spring 605, and the winding 110 of relay 606 to grounded battery. Due to the low resistance of the left-hand winding of relay 220, relays 727, 606 and 220 become energized. The relay 727 locks up through its right-hand armature, front contact and winding, a multiple with relay 714. Relay 115 220 permits the energization of relay 219 and relay 606 causes the movement of sequence switch 600 out of position 6 and into position 7. Upon the opening of the lower left-hand contact of sequence switch spring 120 605, relay 220 becomes deenergized and recloses the above-traced circuit and drives the sequence switch 210 out of position 6 and into position 7. This sequence switch is driven out of position 7 into position 8 by a 125 circuit extending from grounded battery through the power magnet of the sequence switch, the upper right-hand contact of se-

quence switch spring 237, conductor 405 (Figs. 2, 3 and 4) and a contact 404 (closed in response to the actuation of any one of the keys in the stations row), to ground. 5 Since the start key is in the stations column, this circuit will be completed and sequence switch 210 will be moved into position 8.

10 Relay 705 being deenergized a circuit is closed from ground, through the armature and back contact of this relay, conductor 728, the upper right-hand contact of sequence switch spring 609, and the power magnet of sequence switch 600 to grounded battery, for 15 moving this sequence switch out of position 7 and into position 8.

Setting of the incoming brush register.

When sequence switches 210 and 600 reach position 7 $\frac{1}{4}$, a circuit is closed from ground, through the left-hand windings of marginal relay 800 and sensitive relay 801, conductor 802, the lower right-hand contact of sequence switch spring 650, conductor 561, terminal 559, wiper 544, the left-hand contacts of sequence switch spring 560, wiper 575, terminal 577, conductor 225, the upper contact of sequence switch spring 224, the right-hand contact of sequence switch spring 223, the lower right-hand contact of sequence switch spring 245, conductor 246, contact 402 of the No. 9 thousands key, conductor 326 and a relatively high resistance 327 to grounded battery. Due to the high resistance of the circuit, only the sensitive relay 801 becomes energized. This relay closes a locking circuit for itself from ground through its inner front contact, armature and right-hand winding, a conductor 803 and the lower contact of sequence switch spring 621 to grounded battery.

When the two sequence switches reach position 8, a circuit is closed from grounded battery, through the winding of relay 623, the lower left-hand contact of sequence switch spring 651, conductor 652, the left-hand winding of a marginal relay 804, conductor 805, conductor 806, conductor 620, terminal 539, wiper 540, sequence switch contact 565, wiper 528, terminal 579, conductor 566, the upper contact of sequence switch spring 228, the right-hand contact of sequence switch spring 229, the upper left-hand contact of sequence switch spring 247, conductor 248, contact 403 of the thousands key No. 9, conductor 320, conductor 331, the windings of relay 233 and the upper back contact and armature of relay 234 to ground. The relays 623 and 233 become energized. Due to the high resistance of the circuit, the relay 804 does not become energized. Relay 233 opens the shunt around the winding of relay 234 and this relay becomes energized. Relay 623 causes the movement of

sequence switch 600 out of position 8 into position 9, whereupon relay 233 becomes de-energized and moves sequence switch 210 out of position 8 into position 9 in the above de-
scribed manner. Relay 234 becomes de-energized. 70

Setting of the incoming group register.

When the sequence switches 210 and 600 reach position 8 $\frac{3}{4}$, a circuit is prepared from ground through the left-hand winding of a sensitive relay 843, conductor 808, the lower left-hand contact of sequence switch spring 653, conductor 806, conductor 620, terminal 539, wiper 540, the sequence switch contact 565, wiper 528, terminal 579, conductor 566, the upper contact of sequence switch spring 228, the right-hand contact of sequence switch spring 229, the upper right-hand contact of sequence switch spring 247, conductor 249, but in view of the fact that conductor 249 is not connected to any contact of the No. 9 thousands key, this circuit is not completed, and therefore relay 807 remains deenergized.

When the sequence switches reach position 9, a circuit is closed from grounded battery, through the winding of relay 606, the upper left-hand contact of sequence switch spring 654, conductor 655, the left-hand winding of a marginal relay 809, conductor 810, the upper contact of sequence switch spring 603, conductor 561, terminal 559, wiper 544, the left-hand contacts of sequence switch spring 560, wiper 575, terminal 577, conductor 225, the upper contact of sequence switch spring 224, the right-hand contact of sequence switch spring 223, the upper left-hand contact of sequence switch spring 245, conductor 250, contact 400 of the hundreds key No. 8, conductor 401, conductor 330, the windings of relay 220, and the upper back contact and armature of relay 219, to ground. Relays 220 and 606 become energized, and the former permits relay 219 to pull up its armature. Relay 809, however, due to the high resistance of the circuit does not become energized. Relay 606 closes a circuit including the left-hand contacts of sequence switch spring 622, for driving sequence switch 600 out of position 9 and into position 10. Relay 220 becomes then deenergized and closes a circuit through the right-hand contact of sequence switch spring 232, for driving sequence switch 210 out of position 9 and into position 10.

Setting of the final brush register:

When the sequence switches reach position 9 $\frac{3}{4}$, a circuit is prepared from ground through the left-hand windings of marginal relay 811 and a sensitive relay 812, conductor 813, the lower left-hand contact of sequence switch spring 650, conductor 561, 125

terminal 559, wiper 544, the left-hand contacts of sequence switch spring 560, wiper 575, terminal 577, conductor 225, the upper contact of sequence switch spring 224, the right-hand contact of sequence switch spring 223, the lower left-hand contact of sequence switch spring 245, and conductor 251, but then, in view of the fact that the hundreds key No. 8 does not close a contact including conductor 251, this circuit is not completed and relays 811 and 812 remain deenergized.

When the sequence switches reach position 10, a circuit is closed from grounded battery, through the winding of relay 623, the upper left-hand contact of sequence switch spring 651, conductor 656, a left-hand winding of marginal relay 814, conductor 805, conductor 806, conductor 620, terminal 539, wiper 540, sequence switch contact 565, wiper 528, terminal 579, conductor 566, the upper contact of sequence switch spring 288, the right-hand contact of sequence switch spring 229, the lower right-hand contact of sequence switch spring 247, conductor 252, contact 406 of the No. 8 hundreds key, conductor 407, conductor 235, the lower resistance right-hand winding of relay 233, and the upper back contact and armature of relay 234 to ground. Relays 233 and 623 become energized, and the former causes the operation of relay 234. Due to the low resistance of the circuit, relay 814 becomes energized and locks up in the same manner as the other register relays. Relay 623 closes a circuit including sequence switch spring 622, for driving sequence switch 600 out of position 10 and into position 11. Relays 233 and 623 become then deenergized and the former closes a circuit to drive the sequence switch 210 out of position 10 and into position 11. Relay 234 becomes deenergized.

Setting of the final tens register.

When the sequence switches reach position 10 $\frac{1}{4}$, circuit is prepared from ground, through the left-hand windings of a marginal relay 815 and a sensitive relay 816, conductor 817, the upper right-hand contact of sequence switch spring 653, conductor 620, terminal 539, wiper 540, sequence switch contact 565, wiper 528, terminal 579, conductor 566, the upper left-hand contact of sequence switch spring 228, the right-hand contact of sequence switch spring 229, the lower left-hand contact of sequence switch spring 247, and conductor 253, but then, in view of the fact that the No. 7 tens key does not have a contact through which this conductor 253 may be extended, the circuit is not completed and relays 815 and 816 remain deenergized.

When the sequence switches reach position 11, circuit is closed from grounded battery, through the winding of relay 606, the

lower right-hand contact of sequence switch 65 spring 654, conductor 818, the left-hand winding of a marginal relay 819, conductor 810, the upper contact of sequence switch spring 603, conductor 561, terminal 559, wiper 544, left-hand contacts of sequence switch spring 560, wiper 575, terminal 577, conductor 225, the upper contact of sequence switch spring 224, the right-hand contact of sequence switch spring 223, the upper right-hand contact of sequence switch 75 spring 245, conductor 332, contact 408 of the tens key No. 7, conductor 401, conductor 330, the windings of relay 220 in series and the upper back contact and armature of relay 219 to ground. Relays 220 and 606 become energized, but, due to the high resistance of the circuit, relay 819 does not become energized. Relay 220 permits the energization of relay 219. Relay 606 closes a circuit including the left-hand contacts of sequence switch spring 622 for driving sequence switch 600 out of position 11 and into position 12, whereupon relays 220 and 606 become deenergized, and the former moves the sequence switch 210 out of position 11 and into position 12 by a circuit including the upper right-hand contact of sequence switch spring 232. Relay 219 becomes deenergized.

Final tens translation.

When the sequence switches 600 and 210 reach position 11 $\frac{1}{4}$, a circuit is prepared from ground, through the right-hand winding of a relay 832, a conductor 833, the lower contact of sequence switch spring 603, conductor 561, terminal 559, wiper 544, the left-hand contacts of sequence switch spring 560, wiper 575, terminal 577, conductor 225, the upper contact of sequence switch spring 224, the right-hand contact of sequence switch 105 spring 223, the upper left-hand contact of sequence switch spring 243, and conductor 336, contact 418 of the No. 7 tens key, conductor 324 and the low resistance 319 to grounded battery. The relay 832 becomes energized, 110 and locks up in the same manner as the register relays.

Final units translation.

When the sequence switches reach position 12, a circuit is closed from grounded battery through the winding of relay 623, the upper right-hand contact of sequence switch spring 651, conductor 820, the left-hand winding of a marginal relay 821, conductor 806, conductor 620, terminal 539, wiper 540, sequence switch contact 565, wiper 528, terminal 579, conductor 566, the upper contact of sequence switch spring 228, the right-hand contact of sequence switch spring 229, the lower right-hand contact of sequence switch spring 241, conductor 333, contact 409 of units key No. 6, conductor 407, conductor 235, the low re-

sistance right-hand winding of relay 233 and the upper back contact and armature of relay 234, to ground. Relays 233 and 623 become energized and the former permits relay 234 to operate. Due to the low resistance of the circuit, relay 821 also becomes energized and locks up in the same manner as the other register relays. Relay 623 closes a circuit including the right-hand contacts of sequence switch spring 622, for driving sequence switch 600 out of position 12 and into position 13. Relays 623 and 233 become then deenergized and the latter closes a circuit to move the sequence switch 210 out of position 12 and into position 13.

Setting of the final units register.

When the sequence switches reach position 12 $\frac{3}{4}$ a circuit is closed from ground, through the left-hand windings of a marginal relay 822 and a sensitive relay 823, conductor 824, the lower right-hand contact of sequence switch spring 653, conductor 620, terminal 539, wiper 540, sequence switch contact 565, wiper 528, terminal 579, conductor 566, the upper contact of sequence switch spring 228, the right-hand contact of sequence switch spring 229, the upper right-hand contact of sequence switch spring 241, conductor 254, contact 410 of the No. 6 units key, conductor 324, and the low resistance 319 to grounded battery. Due to the low resistance of the circuit, both relays 822 and 823 become energized and lock up through their right-hand windings and conductor 803.

When the sequence switches reach position 13, a circuit is closed from grounded battery, through the winding of relay 606, the lower left-hand contact of sequence switch spring 654, conductor 825, the left-hand winding of a marginal relay 826, conductor 810, the upper contact of sequence switch spring 603, conductor 561, terminal 559, wiper 544, the left-hand contacts of sequence switch spring 560, wiper 575, terminal 577, conductor 225, the upper contact of sequence switch spring 224, the right-hand contact of sequence switch spring 223, the upper right-hand contact of sequence switch spring 243, conductor 255, contact 411 of units key No. 6, conductor 323, conductor 221, the left-hand winding of relay 220 and the upper back contact and armature of relay 219 to ground. Relays 220 and 606 become energized and the former causes the operation of relay 219. Due to the low resistance of the circuit, relay 826 becomes energized and locks up. Relay 606 closes a circuit including the left-hand contacts of sequence switch spring 622, for driving sequence switch 600 out of position 13 and into position 14, whereupon relays 606 and 220 become deenergized and the latter moves

the sequence switch 210 out of position 13 and into position 14. Relay 219 becomes 65 then deenergized.

Setting of the stations register.

When the sequence switches reach position 13 $\frac{3}{4}$, a circuit is closed from ground, 70 through the left-hand windings of a marginal relay 827, and a sensitive relay 828, conductor 829, the upper right-hand contact of sequence switch spring 650, conductor 561, terminal 559, wiper 544, the left-hand contacts of sequence switch spring 560, wiper 575, terminal 577, conductor 225, the upper contact of sequence switch spring 224, the right-hand contact of sequence switch spring 223, the lower right-hand contact of sequence switch spring 243, conductor 334, contact 416 of the start key 414, conductor 338, and the low resistance 339 to grounded battery. Due to the low resistance of this circuit both relays 827 and 828 become energized and lock up through their right-hand windings and conductor 803.

When the sequence switches reach position 14, a circuit is closed from grounded battery, through the winding of relay 623, 90 the lower right-hand contact of sequence switch spring 651, conductor 830, the left-hand winding of marginal relay 831, conductor 805, conductor 806, conductor 620, terminal 539, wiper 540, sequence switch contact 565, wiper 528, terminal 579, conductor 566, the upper contact of sequence switch spring 228, the right-hand contact of sequence switch spring 229, the lower left-hand contact of sequence switch spring 241, 100 conductor 335, contact 415 of the start key 414, conductor 320, conductor 331, the windings of relay 233 and the upper back contact and armature of relay 234 to ground. Relays 233 and 623 become energized, but 105 due to the high resistance of the circuit relay 831 is not energized. Relay 233 permits relay 234 to pull up its armatures. Relay 623 closes a circuit including the right-hand contacts of sequence switch springs 110 622, for driving sequence switch 600 out of position 14 and into position 15, whereupon relay 233 becomes deenergized and causes the movement of sequence switch 210 out of position 14 and into position 15.

Restoration of the keyboard and its controlling apparatus.

When sequence switch 210 reaches position 15, a circuit is closed from ground 120 through the upper armature and back contact of relay 219, the windings of relay 220, conductors 330 and 401, contact 400 of the hundreds key No. 8, conductor 250, the upper left-hand contact of sequence switch 125 spring 245, the left-hand contact of sequence

switch spring 223, conductors 337 and 338, and the resistance 339 to grounded battery. Relay 220 becomes energized, locks up through its left-hand front contact, and by 5 opening the shunt around relay 219, permits this relay to become energized. Another circuit is closed from ground through the upper armature and back contact of relay 234, the windings of relay 233, conductors 331 and 320, contact 403 of the thousands key No. 9, conductor 248, the upper left-hand contact of sequence switch spring 247, the left-hand contact of sequence switch spring 229, conductors 340 and 324, and resistance 319 to grounded battery. The energized condition of relays 220 and 233 depends also on the closure of the following circuits: 1, from ground, through the upper armature and back contacts of relay 219, 10 the left-hand winding of relay 220, conductor 221, conductor 328, contact 408 of the tens key No. 7, conductor 332, the upper right-hand contact of sequence switch spring 245, the left-hand contact of sequence switch spring 223, conductor 337, and the low resistance 339 to grounded battery; and 2, from ground through the upper armature and back contact of relay 234, the right-hand winding of relay 233, conductor 235, conductor 407, the contact 409 of the No. 6 units key, conductor 333, the lower right-hand contact of sequence switch spring 241, the left-hand contact of sequence switch spring 220, conductor 340, and the low resistance 319 to grounded battery.

Relay 233 becomes energized and closes a circuit from ground, through the upper armature and front contact of relay 219, sequence switch spring 258, the left-hand front contact and armature of relay 233, and the power magnet of sequence switch 210 to grounded battery. The sequence switch is moved into position 16, whereupon a circuit is closed from ground, through the lower 45 contact of sequence switch spring 259, conductor 341 and the windings of all the magnets 342 in multiple to grounded battery. The magnets 342 restore the depressed keys to normal and when all the actuated keys are 50 restored, all the relays that were held up through contacts of the keys become deenergized. Relay 219 being maintained energized in position 16 of sequence switch 210, a circuit is closed from ground through the 55 left-hand back contact of relay 220, the lower armature and front contact of relay 219, the left-hand contact of sequence switch spring 232, the armature and back contact of relay 214, conductor 343, the right-hand armature and back contact of relay 344, conductor 345, the left-hand back contact and armature of relay 233 and the power magnet of sequence switch 210 to grounded battery. The

sequence switch 210 is moved out of position 16 and into position 18. The magnets 342 65 become deenergized.

While the sequence switch 210 is moving from position 17 to position 18, a circuit is closed from ground through the upper contact of sequence switch spring 259, the lower 70 contact of sequence switch spring 282 and the power magnet of sequence switch 202 to grounded battery. The sequence switch 202 is moved into position 12, which is the listening-out position.

If no other listening key sequence switch is standing in position 8 at this time, the relay 280 becomes deenergized and causes the movement of another sequence switch, that is standing in position 7, into position 8. 80

By depressing a listening-out key 260, the operator can cause at any time the movement of the listening key sequence switches provided at her position, out of positions 7 or 8 and into position 12.

Should the operator desire to listen in, she would depress the listening-in key 261, closing thus a circuit from the upper left-hand contact of sequence switch spring 201, for driving the sequence switch 202 out of 90 position 12 and into position 1, from which position the sequence switch would be driven into position 7 by the above traced circuit closed through the armature and front contact of relay 103, and the lower right-hand 95 contact of sequence switch spring 201. Depending on the energized or deenergized condition of relays 280 and 281, the operator's telephone set is connected to the cord circuit 105 in position 7 or 8 of the listening 100 key sequence switch.

When the sequence switch 202 moves out of position 8, it opens in contact 208 the locking circuit of relay 211. This relay closes a circuit from ground, through its 105 left-hand armature and back contact, and the lower right-hand contact of sequence switch spring 237, for driving sequence switch 210 out of position 18 into position 1.

The keyboard and its controlling apparatus is now restored to normal and ready 110 for controlling the setting of another sender and set of registers.

District group selection.

As soon as sequence switch 600 reaches position 8, a fundamental circuit is completed from ground through the lower right-hand contact of sequence switch spring 630, the upper contact of sequence switch spring 120 631, the windings of stepping relay 632, the right-hand back contact and armature of relay 633, the left-hand contact of sequence switch spring 615, conductor 564, terminal 557, wiper 538, sequence switch contact 563, 125 wiper 576, terminal 578, conductor 227, the

upper contact of sequence switch spring 226, the lower contact of sequence switch spring 266, conductor 116, the lower left-hand contact of sequence switch spring 115 and the 5 winding of relay 114 to grounded battery. Relay 114 becomes energized and closes a circuit from ground through its left-hand front contact, the upper right-hand contact of sequence switch spring 117 and the power 10 magnet of sequence switch 108 to grounded battery, whereupon the sequence switch 108 is driven out of position 2 into position 3. The relay 114 is then locked up through its right-hand front contact and armature, and 15 the lower right-hand contact of sequence switch spring 115.

Relay 632, upon energization, closes a circuit from ground through its armature and front contact and the winding of stepping 20 magnet 634 to grounded battery.

In position 3 of sequence switch 108, a circuit is closed from grounded battery, through the winding of magnet 119, the upper contact of sequence switch spring 120, 25 and the left-hand front contact and armature of relay 114 to ground. Magnet 119 becomes energized and by attracting its armature presses brush rod 121 of the district selector against the roller 123 continuously rotating in the direction of the arrow. 30

Upon the energization of relay 113^a a circuit was closed from ground through the front contact and armature of this relay, the winding of a trip magnet 128^a to grounded 35 battery. Magnet 128^a by attracting its armature rotated a tripping rod 129, moving thus a tripping finger 130 into the path of a catch 131 provided on the cam 127 by means of which the wipers of set 124 are separated. Before the wipers can engage the 40 lowermost terminals of a bank 126, tripping finger 130, being in engagement with catch 131, causes the removal of cam 127 from between the wipers, allowing the wipers to contact with the terminals of bank 126. It will be seen that if, instead of office key B, the 45 office key A is depressed, then the relay 113 becomes energized and causes the tripping magnet 128 to trip another set of wipers on brush rod 121. In the same manner, depending on the depression of a certain office key or a certain tandem hundreds key, a certain one of the relays 113 will be energized to cause the tripping of one of the 50 five district wiper sets. When the wipers of set 124 reach the lowermost terminals of bank 126, a commutator brush 125 carried by brush rod 121 is in engagement with a conducting segment 133. A circuit is thus 55 closed from ground, brush 125, conducting segment 133, the right-hand contacts of sequence switch spring 115, the right-hand armature, front contact and winding of relay 114 to grounded battery. Due to the

closure of this shunt path, the stepping relay 632, which is connected in series with relay 114, becomes deenergized and permits magnet 634 to move the sender wipers 635, 636 by one step in the direction indicated by the arrow. During the further travel of 65 the district selector 122, brush 125 engages an insulating segment 134 and the shunt is removed from the winding of the relay 114, and relay 632 again becomes energized and causes the energization of magnet 634. The 70 operation of the selector 122 continues in the same manner and the relay 632 operates in response to each step taken by the selector. As above stated, in response to the depression of office key B, the district group register is set to arrest the sender when the wiper 635 engages the terminal No. 3. The translation relay 742 serves to determine whether the sender should be arrested with the wiper 635 on terminal No. 3 in section C or D. If 75 the relay 742 is energized, then, upon the engagement by wiper 635 of the terminal No. 3 in section C, a circuit is established from grounded battery, through the winding of relay 633, conductor 637, the left-hand contact of sequence switch spring 638, conductor 639, the upper left-hand contact of sequence switch spring 640, conductor 641, the upper contact of sequence switch spring 729, the outer armatures and back contacts 80 of relays 717 and 719, the No. 3 terminal in section C, wipers 635 and 636, conductor 642, the left-hand front contact and armature of relay 742, the upper left-hand contact of sequence switch spring 730, conductor 731, the upper left-hand contact of sequence switch spring 643, conductor 644, the left-hand contact of sequence switch spring 645, the back contact and armature of magnet 634, and sequence switch spring 105 646, to ground. In view of the fact that relay 742 was not energized during the setting of the registers, the relay 633 will not become energized when the wiper 635 engages the terminal No. 3 in section C, and 110 thus the sender wipers are permitted to rotate, under the control of the selector 122, by nine steps. Upon the ninth deenergization of magnet 634, the wiper 635 engages the terminal No. 3 in section D, and wiper 115 636 engages the terminals connected to conductor 657, and a circuit is closed from grounded battery, through the winding of relay 633, conductor 637, the lower left-hand contact of sequence switch spring 638, conductor 639, the upper left-hand contact of sequence switch spring 640, conductor 641, the upper contact of sequence switch spring 729, the outer armatures and back contacts 120 of relays 717 and 719, the terminal No. 3 in section D, wipers 635 and 636, conductor 657, the back contact and armature of magnet 634 and sequence switch contact 125 646.

to ground. Relay 633 becomes energized and attracts its armature, opening at its back contact the fundamental circuit, causing thus the deenergization of relay 114, which, by opening its left-hand front contact, causes the deenergization of magnet 119. The wipers are thereupon arrested in contact with the lowermost terminals of the ninth group of trunks leading to an incoming selector. For the purpose of insuring the centering of the district selector wipers, the relay 114 is maintained energized as long as the brush 125 is in engagement with the conducting segment 133. Relay 633 closes a circuit from grounded battery, through its left-hand armature and front contact, the upper left-hand contact of sequence switch spring 647, and the power magnet of sequence switch 613 to grounded battery, causing thus the movement of the sequence switch 613 out of position 2 into position 3.

The sender being in an off-normal position, the contact 648 is closed. As soon as the sequence switch 613 reaches position 3 it closes a circuit from grounded battery through the winding of magnet 634, sequence switch contact 649, off-normal contact 648, the back contact and armature of magnet 634, the back contact and armature of relay 633, to ground. Magnet 634 by interrupting its own circuit causes the stepping of the wipers 635 and 636 in a forward direction until they reach their normal position, when, by opening the above traced circuit at contact 648, they cause the deenergization of magnet 634. Upon the permanent deenergization of magnet 634, a circuit is closed from ground, through the left-hand armatures and back contacts of relay 633 and magnet 634, conductor 657, wipers 635 and 636, the lower left-hand contact of sequence switch spring 647, and the power magnet of sequence switch 613 to grounded battery, whereupon the sequence switch is moved out of position 3 into position 4.

Upon deenergization, relay 114 closes a circuit from ground, through its left-hand armature and back contact, left-hand contact of spring 117 and the power magnet of sequence switch 108 to grounded battery, for moving this sequence switch out of position 3 and into position 6. A circuit is now closed from grounded battery, through the left-hand winding of a test relay 135 and the lower left-hand contact of sequence switch spring 136 to ground. Relay 135 closes a circuit from ground through the lower right-hand contact of sequence switch spring 117, and the power magnet of sequence switch 108 to grounded battery, for moving the sequence switch 108 out of position 6 and into position 7. Supposing that the first trunk of the selected group is busy, a ground is

connected to a test terminal 137 of this trunk 65 in a manner to be hereinafter described. A circuit will thus be closed from ground through terminal 137, wiper 138, the right-hand armature and front contact of relay 136, and the right-hand winding of relay 135 70 to grounded battery, for maintaining this relay energized. Relay 135 being energized, a circuit is closed from ground, through the left-hand armature of this relay, the lower contact of sequence switch spring 120 and 75 the winding of up-drive magnet 119 to grounded battery. Magnet 119 causes the wipers of selector 122 to engage the terminals of the next trunk in the group. If this trunk is idle, the relay 135 becomes energized, and connects ground through the upper left-hand contact of sequence switch spring 136, the right-hand back contact and armature of relay 135, and wiper 138 to the 80 multiples of test terminal 139, preventing 85 thus the seizure of this trunk by another selector 122. A circuit is also completed from grounded battery, power magnet of sequence switch 108, lower left-hand contact of spring 117, left-hand armature and back contact of 90 relay 135 to ground, for moving this sequence switch out of position 7 and into position 11.

The operation of the further selector switches (office, incoming and final selectors) by means of which the desired connection is established is not disclosed in the present application. Briefly stated, these selectors operate in the following manner: In position 4 of the sequence 613, four impulses 95 are received by the sender under the control of the office selector, and in accordance with the setting of the office brush register. After the receipt of the four impulses the relay 633 operates in the above described manner 100 and advances the sequence switch 613 into position 6. One office group impulse is received from the office selector in accordance with the setting of the office group register 105 and the relay 633 operates to advance the 110 sequence switch 613 into position 8. In positions 8, 10 and 12 of the sequence switch 613, the tandem hundreds, tandem tens, and tandem units impulses may be sent out. In view of the fact that, in the present case, the 115 sending of such impulses is not desired, due to the setting of class register sequence switch 706, the sequence switch 613 is advanced from position 7 into position 14. This is accomplished in the following manner: As soon as the sequence switch 613 reaches position 8, a circuit is closed from 120 grounded battery, through the winding of relay 633, conductor 637, the left hand contact of sequence switch spring 638, conductor 639, the lower left hand contact of sequence switch spring 658 and the contact of sequence switch spring 738, to ground. Relay 125

633 becomes energized and closes a circuit from ground through its left hand armature and front contact, the upper left hand contact of sequence switch spring 647, and the 5 power magnet of sequence switch 613, to grounded battery, for moving this sequence switch out of position 8 and into position 9. By opening its right hand back contact, the 10 relay 633 prevents the reestablishment of the fundamental circuit and thus the receipt of impulses by stepping relay 632.

When the sequence switch 613 reaches position 9 the relay 633 becomes deenergized, and a circuit is closed from grounded battery, through the power magnet of sequence switch 613, the lower left hand contact of sequence switch spring 647, the sender wipers 636 and 635, conductor 657, the back contact and armature of magnet 634, and the left hand back contact and armature of relay 633, to ground. The sequence switch 613 moves into position 10.

613 moves into position 14. A circuit is then closed from grounded battery, through the winding of relay 633, conductor 637, the left hand contact of sequence switch spring 638, conductor 639, the lower left hand contact of sequence switch spring 658 and sequence switch spring 738, to ground. Relay 633 becomes energized and moves the sequence switch 613 out of position 10 and into position 11 in the same manner as above described, whereupon relay 633 becomes deenergized and reestablishes the above traced circuit through the lower 35 left hand contact of sequence switch spring 647, for moving the sequence switch 613 into position 12. In this position of the sequence switch 613 the mentioned circuit through the sequence switch spring 738 is again closed for driving the sequence switch 613 out of position 12 and into position 13, whereupon the circuit through the lower left hand contact of sequence switch spring 647 is closed to drive the sequence switch out of 40 position 13 and into position 14.

position 18 and into position 11. The lower left hand contact of sequence switch spring 658 being now open, relay 633 cannot become reenergized. In the meantime, the office selector selected an idle trunk leading to the incoming selector. After the registers shown in Fig. 8 have been set, the incoming selector sends five impulses into the sender in accordance with the setting of the incoming brush register, whereupon the sequence switch 613 is advanced to position 16 in the above described manner, for receiving the group impulses in accordance with the setting of the group register under the control of the incoming selector, whereupon sequence switch 613 is moved into position 18. The incoming selector hunts for an idle trunk in the selected group. Then the sender receives four impulses from the final selector in accordance with the setting

of a final brush register, whereupon the sequence switch 613 is moved again into position 2, but, due to the fact that the sequence switch 600 was moved in the meantime into position 16, the sender receives now the final tens impulses instead of the district group impulses. After the receipt of eight impulses under the control of the final selector, the sequence switch 613 is moved into position 4 and receives now, instead of the office brush impulses, the final units impulses under the control of the final selector. The sender 613 is moved then into position 6, but, under the control of class register sequence switch 706, the sending of stations impulses is prevented. 80

Restoration of cord finder and sender selector.

When upon the setting of the final selector the sequence switch 108 moves out of position 11 and opens the upper right-hand contact of sequence switch spring 112, the relay 545 becomes deenergized and closes a circuit from ground through its right-hand armature and back contact, the lower left-hand contact of sequence switch spring 567, and the power magnet of sequence switch 516 to grounded battery, for moving this sequence switch out of position 15 and into position 16. A circuit is now closed from ground through contacts of sequence switch spring 526, and the winding of magnet 568 to grounded battery, and another circuit from ground through the right-hand contact of sequence switch spring 562 and the winding of magnet 569 to grounded battery. These magnets become energized and press brush rods 530 and 552 against rollers 570 and 571 respectively, constantly rotating in the direction indicated by the arrow. Under the control of the rollers 570 and 571, the cord finder and the sender selector are restored to normal. As soon as the brush 555 of the sender selector reaches its normal position, a circuit is closed from ground through the lower left-hand contact of sequence switch spring 527, brush 555, conducting segment 572, the upper right-hand contact of sequence switch spring 567, and the power magnet of sequence switch 516 to grounded battery, for moving this sequence switch out of position 16 into position 17. The circuit of magnet 569 is now opened. As soon as the cord finder reaches its normal position, a circuit is closed from ground through brush 536, conducting segment 573, the upper left-hand contact of sequence switch 567, and the power magnet of sequence switch 516 to grounded battery, whereupon the sequence switch is moved out of position 17 and into position 18, and opens the circuit of magnet 568. As soon as the allotter 583 is moved into position 1 under

the control of a sequence switch like 516, a circuit is closed from ground through allotter contact 586, the lower right-hand contact of sequence switch 567, and the power magnet 5 of sequence switch 516 to grounded battery, for driving this sequence switch out of position 18 and into position 1. In this position the cord finder and sender selector are under the control of the sequence switch 10 516 which may be again employed in extending an operator's keyboard to an idle sender.

Restoration of the sender and the registers.

When the wiper 520 of the sender selector 15 leaves terminal 551, the locking circuit of relay 608 is broken, and this relay becomes deenergized and closes a circuit through its lower armature and back contact, the lower contact of sequence switch 609 and the power 20 magnet of sequence switch 600 to grounded battery, for driving this sequence switch out of position 16 and into position 18. A circuit is now closed from ground through sequence switch spring 667, upper right-hand contact of sequence switch spring 647 25 and the power magnet of sequence switch 613 to grounded battery, and this sequence switch 613 is driven out of position 7 and into position 1. As soon as it reaches position 1 a circuit is closed from ground through sequence switch spring 611, the right-hand contact of sequence switch spring 612, and the power magnet of sequence 30 switch 600 to grounded battery, and the sequence switch 600 is driven out of position 18 into position 1.

When the sequence switch 600 left position 35 15, the relays of the district group, office group, office brush, and class registers became deenergized, and when the sequence switch left position 16, the relays of the other registers became deenergized.

In the above description, the fundamental 40 circuit for controlling the various selector 45 switches was traced as leading through the lower contacts of sequence switch springs 228 and 226, and the circuit for driving sequence switch 108 out of position 11 was traced as leading through the lower contact of sequence switch spring 224. This 50 will be the case if these circuits are closed when the sequence switch 202 is in the listening-out position 12. Should, however, the closure of any one of these circuits be required while the sequence switch 202 is 55 still in the listening-in position 7, these circuits will be completed through the upper contacts of the mentioned sequence switch springs and the lower contacts of sequence 60 switch springs 269, 266 and 256.

Restoration of the selector switches.

If disconnection is desired, the calling and called subscribers restore their receivers

to the switchhooks. This results in the de- 65 energization of the supervisory relays SR and SR'. The supervisory relays actuate a well-known clearing-out signal at the operator's position, whereupon the operator removes plug 101 from jack 102. The cut- 70 off relay of the calling line becomes de-energized and relay 103 becomes deenergized and closes a circuit from ground through its armature and back contact, conductor 270, the upper contact of sequence 75 switch spring 271, and the power magnet of sequence switch 202 to grounded battery whereupon this sequence switch is moved out of position 12 and into position 1. A circuit is closed thereupon from ground 80 through the back contact and armature of relay 103, conductor 270, the lower contact of sequence switch spring 271, conductor 272, upper left-hand contact of sequence switch spring 107 and the power magnet of 85 sequence switch 108 to grounded battery for moving this sequence switch out of position 16 into position 18. A circuit is now closed from ground through the upper right-hand contact of sequence switch spring 90 136 and the winding of a magnet 179 to grounded battery. The magnet 179, by attracting its armature, presses the brush rod 121 against a roller 180 constantly rotating in the direction of the arrow, whereby 95 the district selector is restored to normal. As soon as it reaches its normal position, a circuit is closed from ground through brush 125, the normal conducting segment 181, the lower left-hand contact of sequence 100 switch spring 107 and the power magnet of sequence switch 108 to grounded battery, for driving this sequence switch out of position 18 into position 1. Magnet 179 becomes de-energized. Then follows the release of the 105 other selectors in the well-known manner.

What is claimed is:

1. In a telephone exchange system, a plurality of lines, means including a connecting circuit for establishing a connection between a calling and a called line, an operator's telephone set, a listening-key switch having two definite stopping positions, means operable in one of said positions for connecting said telephone set to said connecting circuit, other means controllable in the other position of said switch for connecting said telephone set to said connecting circuit, and means controlled in the latter position of said switch for coöperating in the establishment of said connecting circuit. 110 115 120

2. In a telephone exchange system, a plurality of lines, means including a connecting circuit for establishing a connection between two lines, an operator's telephone set, a 125 listening key switch having two stopping positions in which said telephone set may be connected to said connecting circuit, and

means controlled in one of the said stopping positions of said switch for coöperating in the establishment of said connecting circuit.

5 3. In a telephone exchange system, a plurality of lines, means including a connecting circuit for interconnecting said lines, an operator's telephone set, a listening-key switch having two definite stopping positions, a pair of contacts operated in one and another pair of contacts operated in the other position of said switch, circuit extensions for connecting said telephone set through either pair of contacts to said connecting circuit, and means controlled only in one of said stopping positions for coöperating in the establishment of said connecting circuit.

10 4. In a telephone exchange system, a plurality of lines, means including a connecting circuit for interconnecting two lines, an operator's position from which the establishment of said connection is controlled, a plurality of listening key switches, a relay and a telephone set at said position, said switches having two definite stopping positions, a pair of contacts for each of said listening key switches closed in one of said stopping positions for connecting the telephone set to said connecting circuit, an energizing circuit for said relay closed in one of said positions of any one of said listening key switches, a pair of contacts closed in the other position of said switches, and in the other position of said switches, and a connection from the telephone set to said connecting circuit including said latter mentioned contacts and back contacts of said relay.

15 5. In a telephone exchange system, a calling and a called line, means including a connecting circuit and a selectively operable switching device for interconnecting said lines, a plurality of senders each arranged to control the operation of said selectively operable switching device, an operator's position comprising a sender controlling apparatus, a telephone set and a listening key switch having two listening-in positions, means for establishing a controlling circuit between said controlling apparatus and any one of said senders, and contacts in said controlling circuit closed only in one of the listening-in positions of said listening key switch.

20 6. In a telephone exchange system, a calling and a called line, a connecting circuit, means for extending one end of said circuit to said calling line, an operator's position comprising a first and a second relay and a telephone set, a plurality of listening key switches at said operator's position, each switch having a normal, a first and a second listening-in and a listening-out position, means operable in response to the connec-

25 tion of said calling line to said connecting circuit for moving one of said listening key switches from normal into the first listening-in position, a talking circuit closed in said first listening-in position of said switch between the operator's telephone set and the calling line, an energizing circuit for said first relay closed by any one of said listening key switches when in the first listening-in position, an energizing circuit for said second relay closed by any one of said listening key switches when in the second listening-in position, a circuit for moving any listening key switch out of the first and into the second listening-in position controlled by a back contact of said second relay, means including back contacts of said first relay and contacts of a listening key switch closed in the second listening-in position of said switch for connecting said operator's set to said connecting circuit, a selectively operable switching device for connecting said connecting circuit to the called line, a sender for controlling the operation of said switching device, a sender controlling apparatus at said operator's position, controlling circuits leading from said controlling apparatus to said sender closed only in the second listening-in position of a switch, and means operable upon the completion of the operation of said controlling apparatus for moving a listening key switch out of the second listening-in position into the listening-out position.

30 7. In a telephone exchange system, a plurality of lines, means including a connecting circuit and selectively operable switching devices for interconnecting two of said lines, an impulse controlling device for controlling the operation of said switching devices, an operator's telephone set, a listening key switch having two stopping positions in which said telephone set may be connected to said connecting circuit, and means actuated in one of said stopping positions of said listening key switch for connecting the impulse controlling device to a switching device.

35 8. In a telephone exchange system, a plurality of lines, means including a connecting circuit and selectively operable switching devices for interconnecting two of said lines, an impulse controlling device for controlling the operation of said switching devices, an operator's telephone set, a listening key switch having two stopping positions in which said telephone set may be connected to said connecting circuit, and means actuated in only one of said stopping positions of said listening key switch for connecting the impulse controlling device to a switching device.

40 9. In a telephone exchange system, a calling and a called line, means including

a connecting circuit and a selectively operable switching device for interconnecting said lines, a sender for controlling the operation of said selectively operable switching device, an operator's position comprising a sender controlling apparatus, a telephone set, a listening key switch having two listening-in positions, means for establishing a controlling circuit between said controlling

apparatus and said sender, and contacts in 10 said controlling circuit closed only in one of the listening-in positions of said listening key switch.

In witness whereof, I hereunto subscribe my name this 20th day of March, A. D. 15 1917.

ALBEN E. LUNDELL.
